UNITED STATES PATENT OFFICE.

CHARLES GLUCKMAN, OF NEW YORK, N. Y.

HANDLE.

Application filed February 3, 1921. Serial No. 442,118.

To all whom it may concern:

Be it known that I, CHARLES GLUCKMAN, a citizen of the United States, and a resident of the borough of Manhattan, city, county, 5 and State of New York, have invented certain new and useful Improvements in Handles, of which the following is a specification.

The present invention relates to improvements in handles for use in connection with hand bags or other carriers and wherein a maximum of stability and high water and moisture resisting properties are required of the handle together with lightness, smoothness of surface and low cost to manufacture.

The general object of the invention is the provision of a handle formed of compressed fibrous material such as paper board and having the required maximum of moisture 20 and water resisting properties required of a device of this kind, together with a smoothness of surface and adaptability for exterior finish with a coloring agent so that the handle may be made to simulate the 25 material of which the bag is formed; and further, having a minimum of weight and the stable properties of the better grade of handles, together with a construction of parts adapted to be united in a simple and 30 expeditious manner without the use of thread or a relatively tedious and expensive stitching operation.

To these ends the invention resides in a shell or body formed of oppositely disposed 35 matching sections of compressed fibrous material such as paper board having peripheral flanges and an insert disposed between the sections and adhesively secured thereto thereby operating to reinforce the sections 40 and co-operate with the flanges which are adhesively secured together to firmly unite the sections against displacement. The structure being such that the said sections and insert are assembled while in a relatively pliable state and subsequently subjected to a great pressure in a press and thereby compressed and rendered rigid.

Other objects will appear and be better understood from that embodiment of the 50 invention of which the following is a specification reference being had to the accompanying drawings forming part thereof and in which:

Figure 1 is a side view of a complete

handle made in accordance with my invention;

Figure 2 is a side view of one of the handle sections;

Figure 3 is a detail side elevation of the insert used in the making of the handle;

Figure 4 is a side elevation of the sections of the handle and insert showing the sections assembled and the position of the insert by dotted lines;

Figure 5 is a vertical cross-section on the line 5—5 of Figure 4;

Figure 6 is a view similar to Figure 5 on the line 6—6 of Figure 1;

Figure 7 is an enlarged detail side elevation of one end portion of the handle.

In Figure 1 the shell or body "A" constituting the handle is formed of paper board or the like rendered rigid by compression and additionally reinforced by an insert indicated by 15 in Figures 3, 4, 5 75 and 6, the said insert being formed of any suitable material, preference being given to material corresponding to that forming the shell or body "A".

Sections 5 and 6 which constitute the 80 shell "A" are provided with peripheral flanges 7, 8. The sections correspond or match one with the other and the flanges provide generous bearing surfaces for an adhesive which is applied to the flanges, and 85 thereby operates to unite the said sections.

The portions of the sections flanked by the flanges 7 and 8 have their inner faces provided with longitudinal concave depressions 9 which impart a rotundity to the outer faces 90 of the sections and thereby adapt these when assembled as shown in Figures 1 and 6 to provide a shell or body with the usual round contour. The insert 15 is substantially semi-

annual in cross-sectional contour and extends longitudinally of the shell or body "A" 95 to points adjacent to the ends thereof. The adjacent surfaces of the insert and sections are secured together by an adhesive so that the presence of the insert not only operates 100 to reinforce the sections 5 and 6 against collapse but co-operates with the flanges 7 and 8 to unite the sections 5 and 6. This structure moreover permits the trimming or removal of the portions of the flanges on the 105 inner side of the shell or body "A", so that the inner side portion, which is embraced by the hand when the handle is in use is smooth

and uninterrupted and free from sharp edges which would impart contusions to the hand.

From the foregoing it will be obvious that the flanges on the inner sides of the sections are provided in order to facilitate assembling of the sections and upon removal of the said flanges the adjacent abutting edges are held by the action of the adhesive coating applied thereto and by the insert 15. By referring to Figures 1, 6 and 7 it will be noted that the flanges 7 and 8 flank the outer sides and opposite ends of the sections 5 and 6 and merge into the inner sides of the said sections at points beyond the portion of the inner section which is usually grasped by the hand when the handle is in use. This construction is of importance in that a maximum amount of bearing surface is provided for the sections without presenting obstructions which would be harmful to the hand or otherwise undesirable.

The sections 5 and 6 are pierced transversely adjacent to their opposite ends so as to provide the openings 10 and 11 for the reception of the usual links or carriers which operate to connect the handle to a hand bag or the like. In Figures 1 and 7 split metallic bushings 12 and 13 are disposed in the openings 10 and 11 and form bearing surfaces for the said links. The radius of the curvature of the body portion of the bushings is greater than that of the openings 10 and 11 but the split in the bushings permits contraction thereof and ready insertion into the openings. The bushings are formed of resilient material which is under tension in the openings 10 and 11 and thereby frictionally binds on the walls of said openings so that rotation of the bushings is prevented. The outer sides of the bushings are beaded so as to provide round bearing surfaces for the links and prevent rubbing thereof with the adjacent surfaces of the sections 5 and 6. The construction of the bushing just described is of importance in a device of this kind where it has heretofore been customary to expand the openings for the bushings to permit of the insertion of the bushings therein. In instances where the material forming the handle had insufficient resiliency to contract so that the opening would assume its normal sized after being expanded, the handle soon gave evidence of weakening at these points by reason of the play of the bushings due to the enlarged openings. With the present construction it will be observed that the bushings may be readily contracted and upon insertion, will automatically compensate by virtue of their being under tension for any enlargement of the openings 10 and 11 through normal wear.

The sections 5 and 6 are cut from a blank

or blanks of suitable fibrous material such as paper board, by a die or the like. The depressions 9 and the flanges 7 and 8 may be formed simultaneously with the cutting of the sections or otherwise, if preferable or desirable. The insert 15 is cut from a blank of fibrous material such as paper board and subsequently formed into the shape shown by the use of dies. In assembling the parts the outer surface of the insert is coated with an adhesive also applied to the face of the depressions 9 and the insert is then disposed between the sections and the flanges 7 and 8 having been coated on their inner surfaces with an adhesive, the parts are brought together as indicated in Figure 5. The assembled parts are then placed in a suitable press and subjected to a high degree of pressure. This pressure operates to compress the relatively pliable sections 5 and 6 so that these are rendered rigid. In this connection it may be stated that the insert 15, prior to assembling the same with the sections, may be compressed and hardened in a suitable press as indicated for the said sections 5 and 6.

The duration of pressure and the amount thereof required for rendering the shell rigid will, of course, vary with the material used for the shell. In the case of paper board a different time will be required than for ordinary pasteboard. The type of pressure employed is that known as cold pressure in that the parts of the die employed in the press are not heated in the same sense that heat is applied to an ordinary heated die. After the compression or hardening of the parts, the handle is taken to a trimming machine and the flanges are trimmed at the lower or inner portion as already described and as indicated in Figures 1 and 6. It will be noted that in the trimming operation portions of the outer flanges are also removed as will be seen by comparing Figure 5 with Figure 6 the presence of the slight protuberance of the outer side of the handle resulting from the remaining portions of the flanges 7 and 8 will not be harmful or injurious to the hand in that these protruding portions will not produce downward pressure on the hand when the handle is in use.

The degree of compression applied to the shell renders the same of relatively fine texture and suitable for receiving a coating of suitable coloring matter which operates to give the material of the shell an appearance corresponding to that of the body. This is of importance in that an envelope of leather is not necessary to lend attractiveness to the handle and the cost incidental to the provision of such envelope is eliminated. It will be understood that the handle of this invention may be made to

conform to any of the conventional shapes of handles for hand bags, grips and the like. The compression of the material forming this shell renders the same with water and

5 moisture resisting properties corresponding to those in handles of the better grade. The stability of the shell constructed as described is equal to that of the better grades of handles of even greater weight.

10 Although I have shown and described an ideal embodiment of the invention, it is to be understood that I reserve the privilege of adopting all such legitimate changes as may be fairly embodied within the spirit 15 and scope of the invention as claimed.

I claim:

1. A handle comprising two matching members each having concave-convex surfaces and made of fibrous plastic material 20 and flanges surrounding the same, and an insert placed between the matching members and within the concave portions thereof, and extending along the length of the lower joint of the matching members and having 25 a dished shaped cross section throughout its length.

2. A handle comprising two matching members each having concave-convex surfaces and flanges surrounding the same, an 30 insert placed between the matching members and within the concave portions thereof, said matching members having a part of said flanges cut away at the lower portion of the handle and having openings at each 35 end, the openings at the adjacent ends of the matching members registering with each other, and metallic fastening devices extending from one opening to the other registering opening, but only partially 40 around the openings.

3. A rigid handle for hand bags and the like having its rigidity imparted by compression and comprising two matching sections of longitudinal and transverse concavo-convex cross-sectional contour and formed of fibrous material, said sections being provided with peripheral flanges adhesively secured together prior to compressing the section, and an insert of longitudinal and transverse concavo-convex cross-sectional contour disposed between said sections and adhesively secured thereto.

4. A handle for hand bags and the like comprising a shell or body formed of fibrous material rendered rigid by compression and provided adjacent its opposite ends with transverse openings, split resilient bushings of greater radii than the openings and disposed therein and an insert of fibrous material rendered rigid by compression and adhesively secured thereto.

5. A handle for bags and the like comprising a shell or body formed of fibrous material rendered rigid by compression and

provided adjacent its opposite ends with transverse openings and having its outer side flanked by a peripheral flange extending around the ends of the shell and merging in the inner side thereof at points inwardly beyond the said openings, split resilient bushings of greater radii than the openings and disposed therein, and an insert formed of fibrous material rendered rigid by compression and disposed within the shell and adhesively secured thereto.

6. A handle for hand bags and the like comprising companion sections having means to center the same, said means adapted to be subsequently removed, and means 80 disposed interiorly of the sections for securing the same together said means being arranged for engagement with the inner surfaces of said sections for the major portion of their length.

7. A handle for hand bags and the like comprising longitudinally split companion sections having flanges above and below the same for initially centering and facilitating the assembling of the sections, said flanges 90 adapted to be partially or wholly removed subsequent to the assembling of the sections, and an insert within the sections for securing the same together said insert being arranged for engagement with the inner surfaces of said sections for the major portion of their length, and being adhesively secured to the sections.

8. A rigid handle for handbags and the like, comprising two companion sections of longitudinal and transverse concavo-convex cross sectional contour secured together adhesively at their outer edges, and an insert of longitudinal and transverse concavo-convex cross-sectional contour corresponding to the contour of said companion sections, said insert being disposed within the sections over one of the joints between the sections in a manner to extend to a substantially equal extent on both sides of the joint and being adhesively secured to the sections so as to cooperate in binding the sections together.

9. A handle having oppositely disposed sections concave on their inner surface, and convex on their outer surface, joined together at their upper margins by means of flanges formed thereon, and at their lower margins by an edge abutting joint, and a reinforcing plate corresponding in outline with that of the lower inner surface of said sections, extending over said joint, and adhesively secured to the inner surface of the lower margins of said sections.

10. A handle having oppositely disposed corresponding sections, concave on their inner surface, and convex on their outer surface, joined together at their upper margins by means of contact flanges formed thereon, and at their lower margins by an

edge abutting joint, a reinforcing plate corresponding in outline with that of the lower inner surface of said sections, extending over said joint, and adhesively secured to said inner surfaces of the lower margins of said sections, the ends of said sections being provided with apertures, and split resilient

bushings disposed therein, of a greater radii than that of said apertures.

In testimony that I claim the foregoing ¹⁰ as my invention, I have signed my name hereunder.

CHARLES GLUCKMAN.
